UNITED STATES PATENT OFFICE.

SETH WILLIAM BABBITT, OF MERIDEN, CONNECTICUT, ASSIGNOR TO THE INTERNATIONAL SILVER COMPANY, OF SAME PLACE.

DESIGN FOR A BASE MEMBER FOR SOLID OR PLATED METAL WARE.

SPECIFICATION forming part of Design No. 85,092, dated September 17, 1901.

Application filed August 2, 1901. Serial No. 70,673. Term of patent 7 years.

To all whom it may concern:

Be it known that I, SETH WILLIAM BABBITT, a citizen of the United States, residing at Meriden, in the county of New Haven and State of Connecticut, have invented and produced a new and original Design for a Base Member for Solid or Plated Metal Ware; and I do hereby declare the following to be a full, clear, and exact description of the same, reference being had to the accompanying drawings, forming a part thereof.

This invention relates to a new and original design for a base member for solid and plated metal ware, and it is embodied in the formation and configuration with the associated fanciful features presently to be described, and shown in the accompanying drawings.

In the drawings the design is illustrated in side elevation, Figure 1, and in top plan view, Fig. 2.

The general features of the design reside in the hexagonal base with portions between the angles curved inwardly. The upper face of the base is inclined and terminates in a slightly-overhanging cap portion. The surface of the upper face is divided into equal spaces by fanciful ribs of scroll formation

terminating at the base of the cap, at which point suitable scroll projections, which constitute in effect continuations of the ribs, extend upward to the center of the cap portions. Immediately below the overhanging portions or cap and between the rib features are fanciful spray effects, as shown.

The essential features of the design are the general configurations comprising the division of the base by the scroll-like ribs with the slight overhanging portion or cap having projecting fanciful ribs, substantially as shown.

While the design is used for solid and plated metal ware, it is to be understood that its application is not thereby limited.

Having thus described the invention, what is claimed as new, and desired to be secured by Letters Patent, is—

The design for a base member for solid and plated metal ware substantially as shown and described.

In testimony whereof I affix my signature in presence of two witnesses.

SETH WILLIAM BABBITT.
